UNITED STATES PATENT OFFICE.

EDWARD ERICKSON, OF LYNN, MASSACHUSETTS, ASSIGNOR TO VICTOR SHOE MACHINERY COMPANY, OF BOSTON, MASSACHUSETTS, A CORPORATION OF MASSACHUSETTS.

LOOPER MECHANISM FOR SEWING-MACHINES.

1,169,716.

Specification of Letters Patent.

Patented Jan. 25, 1916.

Application filed April 24, 1915. Serial No. 24,137.

To all whom it may concern:

Be it known that I, EDWARD ERICKSON, a subject of the King of Sweden, and a resident of Lynn, in the county of Essex and 5 State of Massachusetts, have invented certain new and useful Improvements in Looper Mechanisms for Sewing-Machines, of which the following is a specification.

This invention relates to looper mechanisms for sewing machines and has for its 10 object the provision of a new device of this character in which the friction upon the various moving parts coacting with a revolute cam member will be reduced to a 15 minimum.

The invention consists in certain novel features of construction and arrangement of parts which will be fully understood by reference to the description of the drawings 20 and to the claims hereinafter given.

Of the drawings: Figure 1 represents a sectional elevation of a portion of a sewing machine having applied thereto a looper mechanism embodying the principles of the 25 present invention. Fig. 2 represents a front elevation of said looper mechanism. Fig. 3 represents a side elevation of the same showing the supporting bearing in section. Fig. 4 represents a rear elevation of the same, 30 and Fig. 5 represents a horizontal section, the cutting plane being on line 5—5 on Fig. 3.

Similar characters designate like parts throughout the several figures of the 35 drawings.

In the drawings, 10 is a revolute shaft having keyed thereto a cam disk 11 having a peripheral cam throw 12 and a peripheral cam path 13. The cam path 13 is preferably 40 concave and adapted to receive a large ball 14 mounted in a raceway of a member 15, said raceway carrying a plurality of anti-friction members such as the small balls 16 on which said ball 14 is adapted to freely 45 rotate. The raceway 15 is secured to one end of a lever 17 pivoted at 18 to the oscillating member 19. The oscillating member 19 is provided with an arm 20 from which extends a lug 20* adapted to support one 50 end of a spring 21, the opposite end of which is positioned on a lug 22 projecting from an arm 23 having at one end a roller 24 engaging the periphery of the cam disk 11 while the opposite end of said arm 23 is

provided with a sleeve 25 surrounding a 55 stud 25* formed upon the oscillating member 19. Both the stud 25* and the sleeve 25 are adapted to oscillate in the fixed bearing 26 forming a part of the main frame of the sewing machine. The stud 25* is provided 60 with a reduced threaded end 27 on which is mounted a nut 28 adapted to prevent the displacement of the oscillating member 19 and the stud 25* from the sleeve 25 and its bearing 26. 65

The arm 23 being interposed between the member 19 and the end of the bearing 26 is prevented from endwise movement but is free to oscillate about the axis of the sleeve 25 in its bearing 26. The spring 21 interposed between the arms 20 and 23 insures the ball 14 seating itself in the path 13 and also causes the roller 24 to remain in contact with the periphery of the disk 11. The lever 17 is provided with tapered studs 30 70 secured thereto by means of the nuts 31. The axes of these studs 30 are parallel and said studs are disposed on opposite sides of the ball 14 with their outer and smaller ends opposite the center of said ball as shown in 75 Fig. 5 of the drawings. These studs 30 prevent the ball 14 from being displaced from the raceway in the member 15 and the anti-friction members 16 mounted therein. It will be observed from an inspection of the 80 drawings that by the construction shown therein the ball 14 is free to move in any direction. 85

The cam disk 11 is provided with a deep recess 32 in the bottom of the cam path 13, 90 this recess or depression 32 being adapted to receive the projecting end of the raceway member 15 so that the surface of the ball 14 may contact with the concaved surface of the cam path 13. It will be observed by 95 an inspection of Fig. 3 of the drawings that the center of the ball 14 is located on one side of the axis of the stud 25*, while the roller 24 is located on the opposite side of said axis. 100

This roller 24 coacting with the periphery of the disk 11 is intended to retain the ball 14 at all times in contact with its cam path 13. The arm 35 extending upwardly from the lever 17 is provided with a split ring 36 105 in which is mounted the looper 37 secured therein by the clamp screw 38. The split ring 36 is pivoted to the end of the arm 35

by said screw 38 by which it may be clamped at any desired angle relative to the said arm 35.

As the needle 39 passes downwardly with its barb below the work support 40, the rotation of the cam disk 11 will cause the looper 37 to be moved in an orbit about the needle 39 and place the thread carried by said looper upon the barb of the needle preparatory to its upward movement through the work.

The machine is provided with the shuttle 41 with a driving mechanism therefor, and also has all the other instrumentalities for the formation of the stitch, but as these devices form no part of the present invention, they are not herein described.

The shaft 10 has mounted thereon a gear 42 which is driven by the gear 43 on the main driving shaft 44. It is evident that the entire looper mechanism is supported from the single bearing 26 and that by the combined operation of the various elements thereof the looper 37 is given the required orbital movement that is necessary to place the loop of thread upon the needle 39.

By mounting the ball 14 upon the smaller ball 16 in the member 15 and between the projections 30 this ball is free to move in any direction when coacting with either the peripheral throws 12 or the side throws 45 of the cam path 13, its free movement reducing the friction of the operating and coacting parts to a minimum.

It will be noted that the shanks of the projections 30 are eccentric to the bases thereof and are provided at their ends with slots by which said projections may be turned about the axes of said shanks, thereby reducing the distance between the adjacent walls of said projections. When thus adjusted the projections are again locked in position by means of the nuts 31.

By this construction whenever the ball 14 becomes worn and reduced slightly in diameter the projections may be adjusted to take up this wear. When the ball becomes too greatly worn to properly operate the looper 37 it may be replaced with a new one without discarding the other parts of the looper operating mechanism. The ball 14, however, will outlive any other construction of cam-path-engaging members owing to its ability to move in any direction about its center.

It will be noted that the ball 14 is retained in contact with its cam path 13 at all times by the action of the spring 21 which can only expand outwardly while the roller 24 is bearing against the periphery of the cam disk. While the ball 14 is passing over the peripheral cam throw 12 the spring 21 will be compressed in an obvious manner and will again expand as soon as said throw 12 has been passed.

It is believed that the operation and many advantages of this invention will be fully understood from the foregoing description.

Having thus described my invention, I claim:

1. In a looper mechanism for sewing machines, the combination of a revoluble disk having a peripheral cam path; a pivoted lever provided with a thin plate extension having therein an annular raceway; a looper secured to the end of said lever; a large ball in said raceway adapted to coact with said cam path; and means carried by said lever on each side of said extension for positioning said ball in said raceway.

2. In a looper mechanism for sewing machines, the combination of a revoluble disk having a peripheral cam path; a pivoted lever provided with an annular raceway having a plurality of antifriction members; a looper secured to the end of said lever; a large ball in said raceway movable on said antifriction members and adapted to coact with said cam path; and means carried by said lever on each side of said raceway for positioning said ball therein.

3. In a looper mechanism for sewing machines, the combination of a revoluble disk having a peripheral cam path; a pivoted lever provided with a thin plate extension having therein an annular raceway; a looper secured to the end of said lever; a large ball in said raceway adapted to coact with said cam path; and a tapered projection from said lever on each side of said extension for positioning said ball in said raceway.

4. In a looper mechanism for sewing machines, the combination of a revoluble disk having a peripheral cam path; a pivoted lever provided with a thin plate extension having therein an annular raceway; a looper secured to the end of said lever; a large ball in said raceway adapted to coact with said cam path; and means carried by said lever on each side of said extension for positioning said ball in said raceway and terminating opposite the center of said ball.

5. In a looper mechanism for sewing machines, the combination of a revoluble disk having a peripheral cam path and a peripheral cam throw; an oscillating device provided with a roll coacting with the periphery of said disk and having a transverse slot therein; a lever pivotally mounted in said slot and having two tapered projections thereon; a looper on the upper end of said lever; a ball revoluble between said projections and positioned within said cam path; and a raceway for said ball carried by said lever and interposed between said projections.

6. In a looper mechanism for sewing machines, the combination of a revoluble disk

having a peripheral cam path and a peripheral cam throw; an oscillating device provided with a roll coating with the periphery of said disk and having a transverse slot therein; a lever pivotally mounted in said slot and having two tapered projections thereon; a looper secured to the end of said lever; a ball revolute between said projections with its center alined with the ends thereof and positioned within said cam path; and a raceway for said ball carried by said lever and interposed between said projections.

7. In a looper mechanism for sewing machines, the combination of a revolute disk having a peripheral cam path and a peripheral cam throw; an oscillating device provided with a roll coating with the periphery of said disk and having a transverse slot therein; a lever pivotally mounted in said slot and having two removable projections thereon; a looper secured to the end of said lever; a ball revolute between said projections and positioned within said cam path; and a raceway for said ball carried by said lever and interposed between said projections.

8. In a looper mechanism for sewing machines, the combination of a revolute disk having a peripheral cam path and a peripheral cam throw; an oscillating device provided with an arm carrying a roll coating with the periphery of said disk and having a transverse slot therein; a lever pivotally mounted in said slot and having two parallel projections thereon; a looper secured to the end of said lever; a ball revolute between said projections and positioned within said cam path; and a removable raceway for said ball carried by said lever and interposed between said projections.

9. In a looper mechanism for sewing machines, the combination of a revolute disk having a peripheral cam path and a peripheral cam throw; an oscillating device provided with a roll coating with the periphery of said disk and having a transverse slot therein; a lever pivotally mounted in said slot and having two parallel projections thereon; a looper secured to the end of said lever; a ball revolute between said projections and positioned within said cam path; a removable member secured to said lever midway of said projections and having a concaved annular raceway; a plurality of small balls in said raceway; and a large ball positioned between said projections in the center of said raceway and adapted to coat with said cam path.

10. In a looper mechanism for sewing machines, the combination of a revolute disk having a peripheral cam path and a peripheral cam throw; an oscillating device having two arms one of which is provided

with an annular raceway and two projections disposed equidistant from said raceway on opposite sides thereof; a large ball in said raceway between and contacting with said projections, said ball being adapted to coat with said cam path; a pivoted arm carrying a roll engaging the periphery of said cam disk; a spring between the other arm of said pivoted device and said pivoted arm; and a looper carried by said oscillating device.

11. In a looper mechanism for sewing machines, the combination of a revolute disk having a peripheral cam path and a peripheral cam throw; an oscillating device provided with a roll coating with the periphery of said disk and having a transverse slot therein; a looper carrying lever pivotally mounted in said slot and having two parallel projections thereon; a ball revolute between said projections and positioned within said cam path; and a raceway for said ball carried by said lever and interposed between said projections.

12. In a looper mechanism for sewing machines, the combination of a revolute disk having a peripheral cam path and a peripheral cam throw; an oscillating device provided with a roll coating with the periphery of said disk and having a transverse slot therein; a lever pivotally mounted in said slot and having two parallel projections thereon; a looper at the upper end of said lever; a ball revolute between said projections and positioned within said cam path; a raceway for said ball carried by said lever and interposed between said projections; and a plurality of antifriction members in said raceway engaging said ball.

13. In a looper mechanism for sewing machines, the combination of a revolute disk having a peripheral cam path and a peripheral cam throw; an oscillating device provided with a roll coating with the periphery of said disk and having a transverse slot therein; a lever pivotally mounted in said slot and having two parallel projections thereon; a looper at the upper end of said lever; a ball revolute between said projections and positioned within said cam path; a member secured to said lever midway of said projections and having a concaved annular raceway; a plurality of small balls in said raceway; and a large ball positioned between said projections in the center of said raceway and adapted to coat with said cam path.

14. In a looper mechanism for sewing machines, the combination of a revolute disk having a peripheral cam path and a peripheral cam throw; an oscillating device provided with a roll coating with the periphery of said disk and having a transverse slot therein; a lever pivotally mounted in said

slot and having two parallel projections thereon; a looper at the upper end of said lever; a ball revoluble between said projections and positioned within said cam path; a member secured to said lever midway of said projections and having a concaved annular raceway; a plurality of small balls in said raceway; and a large ball positioned between said projections in the center of said raceway and adapted to coact with said cam path, said projections terminating at the center of said ball.

15. In a looper mechanism for sewing machines, the combination of a revoluble disk having a peripheral cam path and a peripheral cam throw; an oscillating device having two arms extending in opposite direction from its pivot, one of said arms consisting of a lever mounted on a pivot perpendicular to the axis of oscillation of said device; means for separating the arms of said oscillating device; a roll carried by one arm and contacting with the periphery of said disk; a ball revolvably mounted in the lever arm 25 and positioned in said cam path; and a looper secured to the opposite end of said lever arm.

16. In a looper mechanism for sewing machines, the combination of a revoluble disk 30 having a peripheral cam path and a peripheral cam throw; an oscillating device having two arms extending in opposite direction from its pivot, one of said arms consisting of a lever mounted on a pivot perpendicular to the axis of oscillation of said device; a roller carried by the other arm and contacting with the periphery of said disk; a ball 35 revolvably mounted in the lever arm and positioned in said cam path; a looper secured to the opposite end of said lever arm; and means whereby said roller arm may yield

while said ball is passing over said peripheral cam throw.

17. In a looper mechanism for sewing machines, the combination of a revoluble disk 45 having a peripheral cam path and a peripheral cam throw; a universally mounted device carrying a cam-path-engaging member; a looper secured to said device; and means on said device coacting with the periphery of said disk and yieldingly connected to said cam-path-engaging member for retaining said member in engagement with its cam path.

18. In a looper mechanism for sewing machines, the combination of a revoluble disk 55 having a peripheral cam path and a peripheral cam throw; a universally mounted device carrying a cam-path-engaging member; a looper secured to said device; means on said device coacting with the periphery of said disk; and a resilient member between 60 said co-acting means and said member for retaining said member in engagement with its cam path and said means in contact with 65 the periphery of said disk.

19. In a looper mechanism for sewing machines, the combination of a revoluble disk having a peripheral cam path and a peripheral cam throw; a universally mounted device carrying a looper; two eccentrically mounted tapered projections secured to said device and adapted to be adjusted about their axes; a member interposed between 70 said projections with a raceway therein; and a ball in said raceway with its center in substantial alinement with the ends of said projections.

Signed by me at 4 P. O. Sq., Boston, Mass., this 22nd day of April, 1915.

EDWARD ERICKSON.
